TOY COMFORTER OR THE LIKE

Norma E. MacKenzie, 425 Sussex Drive,
Ottawa, Ontario, Canada

Filed Oct. 15, 1971, Ser. No. 189,810

Term of patent 14 years

Int. Cl. D21—01

U.S. Cl. D34—4 R

FIG. 1 is a front elevation view of a toy comforter embodying my design;

FIG. 2 is a side view of FIG. 1; and

FIG. 3 is a front perspective view of the toy comforter shown in FIGS. 1 and 2.

I claim:

The ornamental design for a toy comforter or the like, as shown.
